UNITED STATES PATENT OFFICE.

CHARLES E. ONGLEY, OF YONKERS, ASSIGNOR TO HIMSELF AND THOMAS W. ROBERTSON, OF NEW YORK, N. Y.

ELECTRIC FIRE ALARM AND EXTINGUISHING APPARATUS.

SPECIFICATION forming part of Letters Patent No. 429,318, dated June 3, 1890.

Application filed December 27, 1889. Serial No. 335,146. (No model.)

To all whom it may concern:

Be it known that I, CHARLES E. ONGLEY, a citizen of the United States, residing at Yonkers, in the county of Westchester and State of New York, have invented a certain new and useful Improvement in Electric Fire Alarms and Extinguishing Apparatus, of which the following is a specification.

The object of my invention is to provide an automatic fire-alarm apparatus of an effective character, the operation of which will indicate the point from which the alarm is sent, and also to provide a simple and effective extinguishing apparatus which may be used in connection with such automatic alarm apparatus.

My invention is especially designed for the protection of buildings, such as factories and hotels, and to accomplish this I place different signal-boxes in various parts of the building, so that if a fire occurs at any place one of the boxes will be released and the number of the box will be signaled at the office of the building or elsewhere. In connection with this signaling system I prefer to provide the building with an extinguishing system consisting of water-pipes extending throughout the building and provided at many points with outlets, suitable valves being provided, the opening of which permits the water to leave the pipes at the outlets controlled by the valve. I arrange the valves to be operated each by an electro-magnet, and at the office or other place where the signal-receiver is situated I connect the valve-magnets to suitable switches, so that as soon as a signal is received the switch controlling the valves nearest to the point from which the signal comes may be closed, so as to open such valve and allow the water to issue from the pipes. I prefer to have each valve provided with two magnets, one for opening and the other for closing the valve, each magnet being controlled by a separate switch.

My invention is illustrated in the accompanying drawings.

Figure 1 is a front view of a signal-box provided with my invention; Fig. 2, a front view of the box with the cover removed, and Fig. 3 a diagram of the system. Fig. 4 is a detail

view of the controlling apparatus of the motor.

The transmitter shown is an ordinary individual transmitter or district call-box consisting of a break-wheel A and contact-spring B, the break-wheel being operated by a spring-motor C, which is placed under tension by turning the handle D, which is outside of the box.

E is a link of fusible wire, such as is commonly employed for automatic fire-extinguishing apparatus, which is placed over the stem a at the end of the handle and over a post or stem b, projecting from the front of the box, the handle being first turned to put the spring-motor under tension. The fusible link holds it in this position until it is released, which will occur when the temperature in the vicinity of the box reaches a point sufficient to melt the fusible metal, whereupon the break-wheel will turn under the contact-spring, as usual, and transmit a signal giving the number of the box. Instead of the fusible link, it is evident that other thermostatic devices may be employed to hold the spring under tension.

Referring now to Fig. 3, boxes F F, of the kind just described, are placed at suitable points throughout the building, these being as shown, all connected in series in a circuit from the battery G, in which circuit is also placed a signal-register H of any suitable character, and preferably, also, a magnet I. In addition to the circuit containing the alarm-box, another circuit extends from the battery to the switch-board K, at which are provided switches or keys of suitable character, controlling the circuits of the valve-operating magnets c c' and d d'. L is a main water-pipe, and M M' are branch pipes, the branch pipes having outlets e, these devices being as usual in automatic sprinkling systems. The branch pipe M has a valve at N, and the pipe M' a valve at N'. These valves are operated by hydraulic pressure, controlled by the magnets—magnets c and d operating to open their respective valves and magnets c' and d' to close them. The energization of magnet c or c' opens one of the small valves v in a supplemental cylinder g. This allows the water, 100

which normally stands in the inlet-pipe L' and the space below valves v and v' , to flow through the upper port h to the space above the piston i , moving it down, the effect being 5 to close valve v'' and open v' . Water then flows through the outlet k to pipe l or m , as the case may be, to move the piston P (see Fig. 3) and open or close the valve in the branch pipe M . The circuit of each magnet 10 is also provided with a push-button f for operating the valves, when it is desired to do so, at a point other than the central office. A magnet I controls a local circuit containing a vibrating bell O in the office, and also, if desired, a similar bell P outside the building.

It will be seen that when any one of the boxes F is released, as above described, a numerical signal showing the number of the box will be registered at the office, and at the 20 same time an alarm will be given by the bells O and P . The person in charge will then at the switch-board close the switch of the magnet for opening the valve nearest to the box from which the signal has been sent, and so 25 cause the water to flow from the pipe at that place. The flow of water may be stopped by closing the key of the valve-closing magnet. The operation of opening and closing the valves may also be performed by means of 30 the push-buttons f , when desired.

What I claim is—

1. The combination, with the water-pipes provided with outlets, valves in said pipes, an electro-magnet for opening and an electro- 35 magnet for closing each valve, circuits including said magnets and extending to the office or similar point, and switches for said circuits, also at the office, of automatic fire-alarm-signal transmitters distributed about the building and a signal-receiver connected therewith, 40 substantially as set forth.

2. The combination, with the water-pipes provided with outlets, valves in said pipes, an electro-magnet for opening and an electro-magnet for closing each valve, circuits including 45 said magnets, and switches for said circuits, of individual spring-operated signal-transmitters distributed about the building and each provided with a thermostat for holding it under tension, and a signal-receiver 50 connected with said transmitter, substantially as set forth.

3. The combination of a water-pipe, a branch pipe therefrom, a valve in the branch pipe, a water-motor connected with the main pipe for 55 opening and closing the valve, magnets for controlling admission of water to one side or the other of the motor as it is desired to open or close the valve, and independent circuits for the opening and closing magnets leading 60 to the office, and circuit-controllers in each circuit at said office, substantially as described.

4. The combination of a water-pipe, a branch pipe therefrom, a valve in the branch pipe, a water-motor connected with the main pipe for 65 opening and closing the valve, magnets for controlling admission of water to one side or the other of the motor as it is desired to open or close the valve, independent circuits for the opening and closing magnets leading to 70 the office, circuit-controllers in each circuit at the office, and additional push-buttons at other points of the same circuit, whereby the valves can be operated from several points, 75 substantially as described.

This specification signed and witnessed this 23d day of December, 1889.

CHARLES E. ONGLEY.
